METHOD AND APPARATUS FOR ELEVATING
GRANULAR MATERIAL

Robert M. Shirk, Wilmington, Del., assignor to Houdry Process Corporation, Wilmington, Del., a corporation of Delaware

Application December 29, 1951, Serial No. 264,081

8 Claims. (Cl. 302—53)

This invention relates in general to a method and apparatus for elevating granular solid material by means of a gaseous lift medium. In particular, the invention is directed to a multiple lift in which granular material is conveyed through separate confined lift paths from a common source of distribution to individual engaging zones surrounding the lift inlets, and therein engaged by lift gas in such quantity as to convey the material into and upwardly through the various lift paths to the desired elevation, and in such manner as to maintain substantially uniform flow along the plurality of lift paths.

The invention is especially applicable to petroleum refining and other chemical processing systems wherein gaseous reactants are contacted with a downwardly moving compact mass of granular material, such as catalyst, along a downflow path comprising one or more treating or contact zones, the catalyst being separated from the gaseous reaction products near the lower end of the downflow path and passed downwardly to the introduction zone of a pneumatic lift. Within the introduction zone the granular material is engaged by a stream of lift gas and conveyed upwardly through the lift to a disengaging zone at the desired point of elevation. Within the disengaging zone the lift gas is separated from the granular material and is discharged from the lift system, while the granular material is collected and returned to the upper end of the downflow path for recirculation through the contact or treating zones.

Typical systems to which the present invention may be applied are those discussed generally in an article entitled "The T. C. C. catalytic cracking process for motor gasoline production" by R. H. Newton, G. S. Dunham, and T. P. Simpson, recorded in the "Transactions of the American Institute of Chemical Engineers," volume 41, page 215, April 25, 1945, and in other articles therein cited, and an article entitled "Houdriflow: New design in catalytic cracking" appearing at page 78 of the January 13, 1949, issue of the "Oil and Gas Journal."

The solid material comprising the circulating medium may be a catalyst or other contact material in the form of relatively large aggregates or agglomerated masses, such as pellets, beads, or coarse granules of a particle size in the range of about 0.05—0.25 inch, for example, predominantly comprising particles of an average size in the order of 0.15 inch. In the case of a system for effecting hydrocarbon conversions, the granular material may be of a catalytic nature, and the gaseous lift medium may comprise flue gas, steam, or other inert gas, or it may comprise gaseous hydrocarbons, air, etc.

For convenience of description and illustration the present invention will hereinafter be considered in connection with a catalytic cracking system for converting hydrocarbons in the presence of granular catalyst gravitating as a compact non-turbulent mass.

In connection with the elevation of the catalyst for recirculation, both mechanical lifts and pneumatic lifts have heretofore been employed. Mechanical lifts, such as those employing continuously rotating bucket chains,

2

however, have in many instances been found impractical for various reasons, such as high initial costs, limited conveying capacity, excessive wear of the moving parts because of the difficulty in maintaining proper lubrication at the extremely high temperatures employed, and the necessity for providing special devices to accommodate elongation of the bucket chain as a result of temperature change, which may be of considerable amount in lifts that are several hundred feet in height.

10. In pneumatic systems, to which the present invention relates, many of the difficulties encountered with mechanical lifts are avoided. Pneumatic systems, however, have their own characteristic problems, especially with respect to the avoidance of excessive catalyst attrition and erosion of mechanical parts, and to the maintenance of uniform catalyst flow through the lift system. The problem of maintaining uniform catalyst flow is especially acute in multiple lift systems wherein catalyst is supplied directly to the various lift pipes from a common bed or source of distribution containing the inlets to the lift pipes. In such systems, erratic performance within one of the lift pipes may produce pressure fluctuations of sufficient magnitude at the lower or inlet end thereof to create an adverse pressure differential between the inlet end of the faulty lift pipe and the inlet ends of adjacent lift pipes. In such case, lift gas introduced adjacent the inlet of the erratically performing lift pipe may by-pass through the compact mass of catalyst surrounding the lift inlet to the inlet of the adjacent lift pipe, thus adversely affecting its performance and the performance of the lift system as a whole. The problem becomes especially acute when the shortest available path for the gas to flow through the compact mass of catalyst from one lift inlet to an adjacent inlet does not provide a resistance to flow which is sufficient to overcome the adverse pressure differential existing between the respective lift pipe inlets. Experience has shown that, for various reasons, minor fluctuations in catalyst flow within the several lift pipes are inevitable during normal operation of the lift system. When the inlet ends of the multiple lift pipes are not sufficiently segregated within the downflowing mass of catalyst, gas migration from the region surrounding an erratically operating lift pipe to the inlet of one or more adjacent lift pipes having a substantially lower inlet pressure, is inevitable. The effect of lift gas migration away from the faulty lift pipe is cumulative. If migration continues, it may cause a complete interruption of catalyst flow in the faulty lift pipe and may adversely affect the operation of the remaining lift pipes by increasing the velocity of catalyst flow therein beyond acceptable limits. This may occur regardless of whether the segregation is provided within a common engager vessel or is provided by separate engager vessels for each of the lift pipes.
15. In accordance with the present invention, uniformity of solids flow through the several lift paths of a multiple pneumatic lift, having segregated inlets fully submerged within separate confined downwardly-moving compact columns continuously supplied with granular material from a common source of distribution, is obtained by introducing the major portion of lift gas around and adjacent to the lower periphery of each lift path, introducing a minor portion of lift gas at an intermediate level along the outer periphery of each compact column and at a location spaced laterally outward from the major stream of lift gas, and varying the amount of the minor portion of lift gas in accordance with changes in pressure occurring within each lift path.
20. In a preferred method of carrying out the invention, both streams of lift gas are discharged downwardly into each column of granular material, and the stream constituting the minor portion of the total lift gas is intro-

25. 30. 35. 40. 45. 50. 55. 60. 65. 70.

duced at a rate insufficient of itself to effect the elevation of the granular material through the lift path.

The method of the invention does not preclude the incidental introduction into the compact moving column of additional small amounts of sealing gas conveyed thereto with the granular material, provided the substantial major portion of the total gas entering each lift path is supplied, as aforesaid, adjacent its lower perimeter.

A fuller understanding of the invention may be had by reference to the following description and claims taken in connection with the accompanying drawing illustrating a typical system including a hydrocarbon conversion unit, hereinafter called a unitized reactor, comprising in a single vessel superimposed zones including a conversion zone wherein the conversion is effected in the presence of downwardly moving catalyst, and a regeneration zone wherein carbonaceous material formed on the catalyst during the conversion is removed by combustion in the presence of oxygen-containing gas. In the drawing:

Fig. 1 is a schematic view in elevation showing the unitized reactor provided with a multiple lift comprising four lift pipes disposed between the unitized reactor and a conventional storage vessel; and

Fig. 2 is an enlarged fragmentary sectional view of one of the lift engagers shown in Fig. 1.

Since the invention is directed primarily to the operation of the multiple lift system, and since the design and operation of the hydrocarbon conversion unit is similar in major respects to that described in the aforementioned article appearing in the "Oil and Gas Journal," illustration and description of the unitized reactor in great detail have been omitted for the sake of brevity.

Referring to Fig. 1 of the drawing, the unitized reactor vessel is indicated by the numeral 11. Granular catalyst in an amount sufficient to provide a surge for the system is contained within a surge chamber located in the upper end of the vessel 11. The catalyst is passed downwardly from the surge chamber through the entire vessel 11 as a compact moving mass, passing thereafter successively through: a conversion zone wherein the catalyst is contacted with gaseous hydrocarbons, or both gaseous and liquid hydrocarbons, under conditions suitable to effect the desired conversion; a disengaging zone wherein the gaseous products of conversion are disengaged from the catalyst and are separately discharged from the vessel; a regeneration zone wherein the catalyst is contacted with oxygen-containing gas to remove by combustion the deposit of carbonaceous material formed thereon while passing through the conversion zone; and a disengaging zone wherein the gaseous products of regeneration, or flue gases, are discharged from the regenerated catalyst and are separately discharged from the vessel.

The reactivated catalyst is passed downwardly from the bottom of the vessel 11 through a vertical conduit 12 into a catalyst distributing chamber 13 axially below the vessel 11. The catalyst flows from the lower end of the conduit 12 directly onto a compact moving bed within the distributing chamber of sufficient capacity to provide a continuous uniform flow of catalyst to the various lift pipes.

From the lower end of the distributing chamber 13, the catalyst is passed downwardly and laterally through a plurality of feeder conduits 14 to a corresponding plurality of lift engagers 15, grouped symmetrically below and to one side of the vessel 11, in each of which the catalyst flows downwardly as a compact moving column 16, as shown in Fig. 2. The feeder conduits 14 form with the distributor 13 and the vertical conduit 12 a continuous seal leg between the lower end of the vessel 11 and the lift engagers 15. A vertical lift pipe 17 extends upwardly from a low point within each compact column of catalyst 16. The vertical height of the column 16 is determined by the discharge level of conduit 14, and its surface 18 is inclined downwardly from the end of con-

duit 14 at the angle of repose for the particular catalyst. The lift pipes 17 are grouped as close to the vessel 11 as is practicable. In the illustrated embodiment of the invention four lift pipes arranged in a rectangular group are employed. Only two of the group are visible in the elevational view of Fig. 1. It is contemplated, however, that any suitable number and arrangement of lift pipes may be provided. Lift gas, supplied to the engagers 15 through upper primary inlet conduits 19 and lower secondary inlet conduits 21, engages the catalyst in the lower region of the vessels 15 and conveys the same into and upwardly through the lift pipes 17.

At the top of the lift, the pipes 17 discharge upwardly into a common disengager vessel 22 wherein the catalyst is disengaged from the lift gas. The separated lift gas is discharged overhead from the vessel 22 through conventional fines removal devices, and the separated catalyst is discharged downwardly through conduit 23 to the surge chamber at the upper end of vessel 11.

Referring again to the inlet portion of the lift system, clearly illustrated in the enlarged fragmentary sectional view of Fig. 2, each lift engager 15 comprises a hollow cylindrical member 24 concentrically surrounding the lower end portion of the lift pipe 17, and closed at its upper and lower ends by end plates 25 and 26, respectively. The lower end plate 26 is provided with a valve-controlled drain conduit 27, through which the catalyst may be drained from each lift when the system is shut down. The feeder conduit 14 is connected to one side of cylindrical member 24 at a point spaced from its upper end, and a feeder conduit 28, forming the discharge outlet of a catalyst storage vessel 29, is connected to the opposite side of vessel 24 at a level above the discharge level of conduit 14. A cylindrical sleeve member 31 is concentrically positioned between the lift pipe 17 and the cylindrical member 24. The sleeve 31 extends upwardly beyond the upper end plate 25 of the cylindrical member 24. An end plate 32 seals the upper end of the annular passage 33 formed between the lift pipe 17 and the sleeve member 31.

Primary lift gas is introduced into the annular passage 33 through the conduit 19 connected to the upper end portion of the sleeve 31, the lift gas traveling downwardly through the annular passage 33 and discharging in an annular stream about the lower periphery of the lift pipe 17. The annular stream of primary lift gas engages the catalyst flowing inwardly below the lower end of the sleeve and carries the same upwardly into the mouth of the lift pipe. The lower end of the sleeve 31 preferably terminates slightly below the lower end of the lift pipe 17, as shown. An adjustable sleeve extension, not shown, may be provided at the lower end of the sleeve 31, however, in order to make the sleeve position adjustable to a level above or below the end of the lift pipe. Lift gas is supplied to the inlet conduits 19 from a manifold 34 connected to a source of lift gas through conduit 35. Such lift gas constitutes the major portion of the total lift gas.

The secondary lift gas is supplied to inlet conduits 21 from a manifold 36 connected to a source of lift gas through conduit 37. The secondary lift gas discharges from inlet 21 into a catalyst-free annular passage 38 formed between the cylindrical member 24 and a secondary sleeve member 39 concentrically positioned between the member 24 and the primary sleeve member 31. The upper end of secondary sleeve member 39 is secured to the inner wall of member 24 above and adjacent to the inlet 21 by a ring 41, which also closes the upper end of passage 38. The lower end of sleeve 39 should be at or above the level of the lower end of sleeve 31. If above such level, the distance should not be so great as to introduce an adverse pressure drop from the periphery of the column of catalyst to the lift pipe inlet. Thus, the annular column of moving catalyst 16 is constricted as it passes downwardly between the member 24 and the

secondary sleeve 39. The expansion of the column 16 after it passes the lower end of sleeve 39 causes an exposed annular surface 42 of the catalyst to be formed, the surface 42 forming the lowermost boundary of passage 38. The secondary lift gas enters the downwardly moving annular column 16 uniformly about the outer periphery thereof at a single level, and travels concurrently with the catalyst a relatively short vertical distance to the level where it flows inwardly under the sleeve 31. The pressure drop from inlet 21 to the lift path is therefore relatively small, thus maintaining the pressure requirements in supply line 37 advantageously low. Such secondary lift gas introduced through inlet 21 should in no case constitute more than a relatively minor portion of the total lift gas, preferably not more than 25% of the total gas, and insufficient in amount to alone effect the elevation of the catalyst through the lift pipe.

Since even relatively minor amounts of lift gas flowing concurrently with the catalyst toward the lift inlet exert a strong controlling influence on the rate of catalyst flow through the lift pipe, such secondary gas is, in accordance with the invention, used as a process control to regulate catalyst flow.

While the illustrated embodiment of the invention discloses a single disengager for the group of four lift pipes, it is to be understood that individual disengagers may be provided for each of the lift pipes.

The size and arrangement of the lift apparatus and transfer conduits connected therewith are such that pressure fluctuations occurring at the lower end of any one lift by reason of catalyst accumulation therein, will not be reflected at the inlets of one or more of the remaining lifts. By reason of the relatively long path of flow required for any gas attempting to migrate from the region surrounding one lift inlet to another lift inlet, a sufficient resistance to gas flow is imposed to preclude a gas migration for all pressure fluctuations normally to be expected. Because of the substantial pressure drop through the mass of catalyst in the path extending from one lift inlet to another lift inlet, any erratically operating lift will have a substantial period of time in which to correct itself before the resultant pressure fluctuations at the bottom of the faulty lift may be reflected at the other lift inlets.

Each conduit 19 and 21 for introducing lift gas into the separate engagers 15 is provided with a control valve. Thus, conduit 19 has a valve 43 by which the flow of the primary or major portion of the lift gas into the passage 33 may be controlled. Since control of the catalyst rate of flow through the lift pipe is to be effected elsewhere, valve 43 may be manually set to deliver a desired quantity of primary lift gas.

Conduit 21 is provided with a pressure control valve 44 connected through line 45 to a conventional pressure controller 46. Pressure controller 46 is connected by line 47 to a pressure tap 48 in the side of the lift pipe 17 at a point relatively close to the engager, for example, about ten feet above the upper end of sleeve 31. By means of the controller 46, valve 44 may be operated in accordance with pressure conditions within the lift pipe at the level of the pressure tap 48. Since the pressure at tap 48 reflects the operation of the individual lift, the supply of gas to any erratically operating lift may be varied so as to correct the adverse condition. Undesirable accumulations or concentrations of catalyst within a lift pipe, which would tend to cause slugging or other erratic performance, may be overcome by temporarily decreasing the rate of catalyst flow into the mouth of the lift pipe. Such decrease in the rate of catalyst introduction into the lift pipe is readily effected by decreasing the rate of introduction of lift gas through conduit 21. As soon as the erratically performing lift resumes its proper operation, the pressure within the lift at the level of the pressure tap 48 decreases, thereby causing the valve 44 to be actuated by controller 46 so as to increase the rate of gas introduction through inlet 21.

It is to be particularly understood that the invention is not limited to any specific number of lift pipes or to any specific arrangement thereof. The invention is also not limited with respect to the manner of introducing lift gas into the lift engagers. The lift gas may be introduced at any one or any combination of points herein indicated as being suitable and desirable for the introduction of lift gas. Furthermore, while the illustrated embodiment of the invention shows the catalyst being passed from the lower end of the unitized reactor as a single confined stream to an enlarged distributor, and then from the distributor in separate confined streams to the various lift engagers, it is to be understood that the distributor 13 may be eliminated. In such case, the catalyst may be passed directly from the lower end of the unitized reactor as separate confined streams to the engagers, the length of such separate streams being, of course, sufficient to provide the necessary seal-leg requirements between the unitized reactor and the lift engagers, and the manner of withdrawal from the unitized reactor being such as to distribute catalyst uniformly into each of the confined streams.

Obviously many modifications and variations of the invention as hereinbefore set forth may be made without departing from the spirit and scope thereof, and therefore only such limitations should be imposed as are indicated in the appended claims.

This application is a continuation-in-part of my copending application, Serial No. 226,688, filed May 16, 1951, now Patent No. 2,702,207, Feb. 15, 1955.

What is claimed is:

1. In a cyclic hydrocarbon conversion process wherein granular contact material gravitates as a compact moving mass through a confined downflow path including a contact zone and is then elevated by means of a gaseous lift medium through a plurality of confined lift paths and returned to said downflow path, the method of elevating said granular material through said lift paths which comprises the steps of: passing said granular material from the lower end of said downflow path to each of a plurality of confined engaging zones individual to and enclosing the lower end portion of said confined lift paths and being in fixed, unrestricted open communication therewith; passing said granular material downwardly within each engaging zone as a confined compact annular column surrounding the enclosed portion of said confined lift path; introducing a constant and major portion of lift gas into said engaging zone as a confined stream discharging downwardly therein along and immediately adjacent to the lower perimeter of said confined lift path, thereby initially engaging said granular material as the latter flows downward and radially inward from the lower inner periphery of said annular column; introducing a variable and minor portion of lift gas about the outer periphery of said confined annular column and at a low level therewith; and controlling the amount of said minor portion of lift gas in accordance with pressure changes in the lower end of said lift path, the amount of said minor portion of lift gas being varied in inverse relation to said pressure changes, whereby the rate of flow of said granular material into said lift path is controlled solely by control of said minor portion of lift gas.
2. A method as defined in claim 1, in which said granular material, while flowing from said contact zone to said engaging zone, is passed through a distribution zone adapted to distribute said granular material uniformly to the plurality of engaging zones.
3. A method as defined in claim 1, wherein said minor portion of the total lift gas is introduced into the outer periphery of said moving column at a level adjacent to the level at which said major portion of the total lift gas is introduced.
4. In a hydrocarbon conversion system wherein a continuous circulation of granular contact material is effected by pneumatic elevation thereof through a grouped plu-

rality of lift pipes, the combination of: a tubular sleeve concentrically surrounding the lower end portion of each lift pipe so as to provide therebetween an annular passage for lift gas, said annular passage being closed at its upper end; a tubular vessel concentrically enclosing and extending below said sleeve so as to provide an outer annular passage therebetween for granular material and an engaging zone beneath said lift pipe for accumulation of said granular material and engagement thereof with lift gas, said engaging zone being in fixed, unrestricted open communication with the lower ends of both said outer annular passage and said lift pipe; means for introducing lift gas in major amount into the upper end of said annular gas passage; means for introducing granular material into the upper end of said outer annular passage so as to flow downwardly as a compact unthrottled moving column around said sleeve and into the bottom region of said vessel; means for introducing lift gas in minor and controllable amount into said outer annular passage at a low level along the outer periphery thereof; and means for controlling the flow of said minor amount of lift gas in accordance with pressure change within the lower end portion of said lift pipe.

5. Apparatus according to claim 4 wherein said means for introducing a controlled minor amount of lift gas into said outer annular passage comprises a relatively-short cylindrical member concentrically positioned at the bottom of said outer annular passage and adjacent to the wall of said vessel so as to provide a short annular passage therebetween, said short passage being closed at its upper end and in open communication with said vessel at its lower end; and a conduit including a control valve for introducing lift gas at the upper end of said short passage.

6. Apparatus according to claim 5 wherein said means for controlling the flow of said minor portion of lift gas comprises a pressure controller connected between said

control valve and a pressure tap in the side of said lift pipe.

7. In a process for elevating granular material through an elongated confined lift path by means of a gaseous lift medium wherein said granular material is continuously introduced into a vertically-elongated annular engaging zone containing the lower end portion of said confined lift path and is passed first downwardly around said lift path as an annular elongated compact moving column, 10 and then unrestrictedly inward beneath the lower end of said lift path, the method of introducing said lift gas into said engaging zone to engage and convey said granular material through said lift path which comprises the steps of introducing the substantial major portion of said lift 15 gas into said annular column as a downwardly directed annular stream along the lower perimeter of said lift path, introducing a relatively minor portion of the total lift gas into said annular column along its outer periphery and at a level adjacent to the level of said inlet, 20 and controlling the amount of said minor portion of the lift gas in inverse relation to changes in pressure within the lower region of said confined lift path.

8. A process as in claim 7 in which said changes in pressure are determined near the lower end of said lift 25 path.
